(57) **CLAIM**

The ornamental design for a scooter, as shown and described.

DESCRIPTION

FIG. 1 is a perspective view of a scooter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the scooter where the scooter is in a folded state;

FIG. 10 is an enlarged partial view of the scooter taken from the right side of FIG. 1;

FIG. 11 is an enlarged partial view of the handlebar area taken from the top of FIG. 1;

FIG. 12 is an enlarged partial view of the front wheel area taken from the right side of FIG. 2; and,

FIG. 13 is an enlarged partial view of the rear wheel area taken from the bottom of FIG. 4.

The dash-dot broken lines represent the boundaries of the enlarged partial views of FIGS. 10-13. All other broken lines represent portions of the scooter that form no part of the claimed design. None of the broken lines form a part of the claimed design.
